UNITED STATES PATENT OFFICE.

SAMUEL GRAVER, OF PLAINFIELD, ILLINOIS.

DOUBLE CORNCRIB AND GRANARY.

Application filed May 5, 1923. Serial No. 636,793.

To all whom it may concern:

Be it known that I, SAMUEL GRAVER, a citizen of the United States, residing at Plainfield, in the county of Will and State 5 of Illinois, have invented certain new and useful Improvements in Double Corncrubs and Granaries, of which the following is a specification.

The main purpose of my invention resides 10 in the provision of a building that is well adapted for the storage of grain and corn, the same being divided into separate compartments for the reception of the different elements, the invention being characterized 15 by its simplicity of construction, and high usefulness of purpose.

The nature and advantages of the invention will be better understood when the following detailed description is read in connection 20 with the accompanying drawings, the invention residing in the construction, combination, and arrangement of parts as claimed.

In the drawings forming part of this 25 application, like numerals of reference indicate similar parts in the several views, and wherein:—

Figure 1 is an elevational view of my combined grain bin and corn crib.

Figure 2 is a detail cross section upon the line 2—2 of Figure 1.

Figure 3 is a fragmentary enlarged cross section through one of the partition walls.

Figure 4 is a view similar to Figure 2, but 30 taken upon the line 4—4 of Figure 1.

Figure 5 is a fragmentary section of the concrete grain bin floor, and the supporting beam over the doorway taken on line 5—5 of Figure 1.

Figures 6 and 7 are perspectives of different forms of concrete blocks employed in the construction of the building.

Referring to the drawings in detail, 5 designates the building provided with an inverted cone shaped roof 6 and a ventilated head top 6'.

In the construction of this building, I employ concrete blocks of the type shown in Figures 6 and 7, the block shown in Figure 50 6 being designated 7 and formed with a plurality of spaced ventilating openings 8. The block, Figure 7, is designated 9, and is of a solid nature, it being noted that as shown in Figure 1, the outer wall of the building is 55 constructed from both solid and ventilating

blocks, these blocks being laid one upon the other in the wellknown manner.

In the buildings of this type, the same are provided with a front and rear pair of spaced channel iron posts 10, the building 60 being provided with a vehicle passage-way 11, closed at its opposite ends by swinging doors 12, hingedly secured to the lower end of the said posts 10.

The wall of the building directly above 65 the said swinging doors 12, is constructed of the solid type blocks shown in Figure 7, and extending transversely within the building, and at opposite sides of the said vehicle passage-way 11 are partition walls 13, these 70 walls comprising channel posts 14, between which are disposed the blocks shown in Figure 6. These partition walls 13 are bulged outwardly as shown for the purpose of strength, it being noted that the portions of 75 these partition walls forming the sides of the said vehicle passage-way 11 are formed entirely of the ventilating blocks, Figure 6, while the portions of the walls above the said passage-way are formed by the solid blocks 80 9.

Between the walls 13 and directly above the door opening of the building is a concrete floor while beneath the wall 13, the building floor is provided with steel sills that receive the lower ends of the posts 14, 85 the opposite sides of the concrete floor above the door opening being provided with channel plates 13', that receive the opposite ends of the posts as well as the lowermost ones of the blocks 9, constituting the upper portion 90 of the walls 13.

Connected at their opposite ends to the said channel posts 10 of the building, are stay rods 15, between which are the solid blocks constituting the walls 13 above the 95 door openings. Between each of the partition walls 13 above the vehicle passage-way 11 are other right angular partition walls 16, it being clearly understood that these partition walls 16 as well as the partition 100 walls 13 form compartments centrally within the building for the purpose of receiving grain, while the compartments 18 at the opposite sides of the building are adapted for the reception of corn or the like. 105

The building floor is formed with the usual sheller drag trenches 19 at the opposite ends of which are swinging doors 20.

In view of the above description, it is believed by me that it will at once be apparent 110

that I have provided a building construction, wherein the same may be advantageously used for storing grain and corn, and although I have herein shown and described 5 the preferred embodiment of the invention, it is nevertheless to be understood that minor changes may be made therein, without departing from the spirit and scope of the invention as claimed.

10 Having thus described my invention, what I claim as new, and desire to secure by Letters-Patent is:—

15 A grain crib comprising a foundation which is substantially circular in plan, an exterior wall erected upon the foundation and extending around the peripheral portion thereof, said wall being provided at its diametrically opposite sides with door openings, interior walls disposed transversely of 20 the foundation and connected at their ends

with the exterior walls at the vertical sides of the door openings, and extending the full height of the crib structure, the interior walls being bowed at their intermediate portions away from each other to provide 25 a passageway through the structure from one door opening to the other, a floor located in the structure and dividing the same into a lower and an upper story, the interior walls below the floor being provided with 30 interstices and the interior walls above the floor being completely closed throughout their areas, and transverse walls located above the floor and interposed between the interior walls and spaced from each other 35 and having their intermediate portions bowed inwardly toward each other.

In testimony whereof I affix my signature.

SAMUEL GRAVER.
